US0D1074555S

(12) **United States Design Patent** (10) **Patent No.:** **US D1,074,555 S**
(45) **Date of Patent:** **** May 13, 2025**

(54) **RIM**

(71) Applicant: **VOLVO CAR CORPORATION**, Gothenburg (SE)

(72) Inventor: **Ole-Kristian Bjerke**, Gothenburg (SE)

(73) Assignee: **Volvo Car Corporation**, Gothenburg (SE)

(**) Term: **15 Years**

(21) Appl. No.: **29/893,049**

(22) Filed: **May 24, 2023**

(30) **Foreign Application Priority Data**

Nov. 25, 2022 (EM) 015004285-0013

(51) **LOC (15) Cl.** **12-16**

(52) **U.S. Cl.**

USPC **D12/209**

(57) **CLAIM**

The ornamental design for a rim as shown and described.

DESCRIPTION

FIG. 1 is a front perspective view thereof;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

The broken lines in the drawings are for the purpose of illustrating portions of the rim that form no part of the claimed design.

1 Claim, 8 Drawing Sheets
